DRAIN

Robert H. Shenk, Erie, Pa., assignor to J. A. Zurn
Manufacturing Company, Erie, Pa., a corpora-
tion of Pennsylvania

Application December 16, 1940, Serial No. 370,300

9 Claims. (Cl. 210—43)

This invention relates generally to surface drains and more particularly to drains which prevent sediment, oil, gasoline and the like from passing to the main drain line to which the drain is connected.

All drains of this character made according to the teachings of the prior art and with which I am familiar have had no adequate means for indicating the filling of the straining member in the drain structure, especially in large sized drains. The only way the filling of the straining member was indicated was by the flooding of the area surrounding the surface of the drain. Furthermore, no means have been provided to indicate the presence in the drain of a predetermined head or intercepted oil, gasoline or the like.

It is, accordingly, an object of my invention to overcome the above and other defects in surface drains, and it is more particularly an object of my invention to provide a surface drain which is simple in construction, cheap in cost, efficient in operation, and easy to install.

Another object of my invention is to provide a surface drain which will intercept oil, gasoline, or other liquids lighter than water and to further provide means for indicating the need for removal of the intercepted fluids.

Another object of my invention is to provide surface drains wherein efficient means are provided for indicating the clogging of the straining member of the drain without flooding the drain surface.

Another object of my invention is to provide a simple means for removing the strained refuse from the drain.

Another object of my invention is to provide a surface drain which has all parts thereof removable through the inlet opening.

Another object of my invention is to provide a surface drain wherein a seal is provided to retard the entrance of water and the like upon the head in the straining member attaining a predetermined height.

Another object of my invention is to provide a surface drain which will prevent oil and other substances lighter than water from passing to the drain line.

Another object of my invention is to provide a double seal in a drain line when the liquid in the drain attains a predetermined height.

Another object of my invention is to provide a dead air space between sealing portions of the drain.

Another object of my invention is to provide

sealing means in a drain to prevent volatile gases passing therefrom.

Other objects of my invention will become evident from the following detailed description taken in conjunction with the accompanying drawing in which:

Fig. 1 is a side elevational view in cross section of my novel surface drain.

Fig. 2 is a top plan view of my novel surface drain.

Fig. 3 is a view taken on the line 3—3 of Fig. 1.

Referring to the drawing, Figs. 1, 2 and 3 show a surface drain comprising generally an upper cylindrical member 1 flanged outwardly at 2, and a lower cylindrical member 3 flanged outwardly at 4 for the reception of the lower portion of the cylindrical member 1. Suitable sealing material 5 is provided between the flange 4 and the cylindrical member 1. An outlet 6 in the bottom of the cylindrical member 3 leads to a drain line 7 through a cleanout chamber 8. A back water valve 9 is disposed in the cleanout chamber 8.

Coming now to the gist of my invention, I show a cylindrical straining member 10 having apertures 11 and 12 in the sides and bottom thereof for straining sediment and the like from the water before it passes to the drain line 7. The straining member 10 has an unperforated portion 13 on the upper end thereof and it also has an outwardly extending supporting member 14 which seats on the bottom surface 15 of the outwardly flanged portion 2 of the upper cylindrical member 1. Disposed on the supporting member 14 is a flanged member 16 having a central aperture 17 and two concentrically disposed outer and inner depending flanges 18 and 19. A cup-shaped member 20 is supported by outwardly extending flanges 21 at the base thereof to the bottom portion of the outer depending flange 19. The sides of the cup-shaped member 20 extend above the lowermost portion of the inner depending flange 18. A bar type grate 21 is disposed on and supported by the flanged member 16. The outer depending flange 19 extends a predetermined distance below the inner flange 18.

In operation, water passes through the grate 21 which strains the larger particles of sediment and the like from the liquid passing to the drain. The water and sediment and other liquids pass downwardly to the aperture 17 in the flanged member 16 to the cup-shaped member 20 and overflows therefrom into the straining member 10. The cup-shaped member 20 is of such de-

sign that the solids will be flushed therefrom and not retained therein. A seal is constantly provided between the inner depending flange 18 and the innersides of the cup-shaped member 20 in that the liquids must pass over the sides of the cup-shaped member 20 to reach the straining member 10 and the drain line 7. After the liquid reaches the straining member 10, the sediment is strained therefrom and the water passes laterally outwardly therefrom and passes through the aperture 6 to the drain line 7. Liquids such as oil, gasoline and other liquids lighter than water remain suspended on the top surface of the water in the drain. The outer drain line is of a height which approaches the top row of apertures 11 in the straining member 10, and it is, therefore, necessary to have the liquid in the drain at a greater head than that of the drain line in order that the water will pass outwardly from the drain to the drain line 7. The oil, gasoline or the like suspended on the top of the water continually increases in height until it reaches the bottom of the depending flange 19 whereupon a seal is provided between the cup-shaped member 20 and the depending flange 19. It will be evident that at this point, a double seal is provided, one in the inner and top portion of the cup-shaped member and the other in the outer and lower portion of the cup-shaped member. It will further be seen that a dead air space at this time exists between the two seals. With the double seal and the dead air space, the water entering the drain will be retarded to such an extent that it will be noted by the attendant or other person in the vicinity of the drain. Flooding of the area surrounding the surface of the drain is prevented because upon a sufficient head being present above the grate 21, water will be forced through the double seal and dead air space. An aperture 22 may be provided in the upper cylindrical member 1 to drain off the intercepted oil, gasoline or the like.

It will be evident that I have provided a drain which indicates the filling of a sediment bucket in a drain and further indicates a pre-determined head of oil, gasoline or the like on the surface of the water in the drain, the said drain being so constructed that no flooding of the area of the surface of the drain will take place.

It will be further evident upon inspection that the straining member may be removed through the inlet opening with a minimum of effort. In this construction, the straining member or any part thereof may be simply and easily installed or removed.

Various changes may be made in the specific embodiment of the present invention without departing from the spirit thereof or from the scope of the appended claims.

What I claim is:

1. In a surface drain, in combination, an outer casing member having an outlet in the lower portion thereof, an outlet pipe leading upwardly from said outlet, a removable perforated straining member supported in said outer member, an outlet chamber leading from said outlet in said outer casing upwardly and outwardly at a point in a horizontal plane with the upper portion of said straining member, a centrally apertured member supported in the upper portion of said straining member having an inner depending cylindrical flange and an outer depending cylindrical flange, and a cup-shaped member disposed under and around the lower portion of said inner flange to form a seal between said inner flange and the inner side of said cup-shaped member.

2. In a surface drain, in combination, an outer casing member having an outlet in the lower portion thereof, an outlet pipe leading upwardly from said outlet, a perforated straining member supported in said outer member, an outlet chamber leading upwardly and outwardly from said outlet in said outer casing at a point in the upper portion said outer casing, a centrally apertured member disposed in the upper portion, said outer member having an inner depending cylindrical flange and an outer depending cylindrical flange disposed concentrically of said inner flange, and a cup-shaped member disposed below and around said depending inner flange having the sides thereof disposed above the lowermost portion of said inner depending flange.

3. In a surface drain, in combination, an outer member having a seating surface on the top portion thereof and an outlet in the lower portion thereof, an outlet pipe leading upwardly from said outlet, a perforated straining member having outwardly flared supporting members seated on the seating surface of said outer member, an outlet chamber extending from said outlet in said outer member upwardly and outwardly at a point in a horizontal plane with the upper portion of said straining member, a centrally-apertured member disposed in the upper portion of said outer member having an inner depending cylindrical flange and an outer depending cylindrical flange, the lowermost portion of said outer flange extending below said inner flange, and a cup-shaped member having the sides thereof extending above the lowermost portion of said inner depending flange.

4. In a surface drain, in combination, an outer member having a seating surface on the top portion thereof and an outlet in the lower portion thereof, an outlet pipe leading upwardly from said outlet, a perforated straining member having an unperforated upper portion and having outwardly flared supporting members seated on said seating surface on said outer member, a centrally-apertured member disposed in the upper portion of said outer member having an inner depending cylindrical flange and an outer depending cylindrical flange extending below said inner flange, and a cup-shaped member disposed below said inner flange having the sides thereof extending above the lowermost portion of said inner flange and an outlet chamber extending upwardly and outwardly from said outlet in said outer member to a point in substantially the same horizontal plane with the lower side of said outer depending flange.

5. In a surface drain, as set forth in claim 4, wherein a grate is disposed on said centrally-apertured member.

6. In a surface drain, in combination, an outer cylindrical member having a seating surface on the top portion thereof and an outlet in the lower portion thereof, an outlet pipe leading upwardly from said outlet, a perforated straining member supported on said seating surface on said outer member in spaced relationship thereto, a centrally-apertured member supported by said straining member having an inner depending annular flange and an outer depending annular flange extending below said inner flange, an outlet chamber extending from said outlet in said outer member upwardly and outwardly at a point in substantially the same horizontal plane with the lower edge of said outer depending flange, and a cup-shaped member disposed under said centrally-apertured member and having its sides

extending above the lowermost portion of said inner flange.

7. In a surface drain, in combination, an outer cylindrical member having an inlet and an outlet in the lower portion thereof and an aperture for draining off intercepted material, an outlet pipe leading upwardly from said outlet, a perforated straining member supported in said cylindrical member, a centrally-apertured member supported above said straining member having an inner depending flange and an outer depending flange extending below said inner flange, an outlet chamber extending upwardly and outwardly from said outlet in said outer member at a point in substantially a horizontal plane with the lower edge of said outer depending flange, and a cup-shaped member disposed under and around said inner flange and having its sides extending above the lowermost portion of said inner flange.

8. In a surface drain, in combination, an outer cylindrical member having an inlet and an outlet in the lower portion thereof, an outlet pipe leading upwardly from said outlet, a perforated straining member supported thereon, a centrally-apertured member above said straining member having an inner depending flange and an outer depending flange extending below said inner

flange, an outlet chamber extending upwardly and outwardly from said outlet in said outlet member at a point in substantially the same horizontal plane as the lower edge of said outer depending flange, and a cup-shaped member disposed under and around said inner flange having its sides extending above the lowermost portion of said inner flange, said inner flange and the inner side of said cup-shaped member and the outer flange and the lower portion of said cup-shaped member providing a double seal when the level of the liquid of said drain extends above the lowermost portion of said outer flange.

9. A surface drain, comprising an outer member having an outlet in the lower portion thereof, an outlet chamber, an outlet pipe leading upwardly from said outlet, a perforated straining member having an unperforated upper portion extending above said outlet chamber, a centrally-apertured member disposed in the upper portion of said straining member having an inner depending annular flange and an outer depending annular flange extending below said inner flange, and a cup-shaped member disposed below said inner flange having the sides thereof extending above the lowermost portion of said inner flange.
